(57) **CLAIM**

The ornamental design for a headlamp for motorcycles, as shown and described.

DESCRIPTION

FIG. 1 is a front elevational view of a headlamp for motorcycles showing my new design;

FIG. 2 is a left side elevational view thereof;

FIG. 3 is a right side elevational view thereof; and,

FIG. 4 is a front left perspective view thereof.

The claimed design is a headlamp for motorcycles, the portions of which are shown in solid lines in the drawings, and the broken line portions are provided for the purpose of illustrating an adjacent portion of the motorcycle and form no part of the claimed design.
